(57) **CLAIM**

The ornamental design for a polygonal partition, as shown and described.

DESCRIPTION

FIG. 1 is a top, right, front perspective view of a polygonal partition;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The surface lines shown in the figures represent surfaces of materials that are transparent or semi-transparent.

The broken lines illustrate portions of the polygonal partition that form no part of the claimed design.
